(57) **CLAIM**

The ornamental design for a latch turn mechanism, as shown and described.

DESCRIPTION

FIG. 1 is a perspective view of the latch turn mechanism in accordance with the present invention.

FIG. 2 is a front elevational view of the latch turn mechanism of FIG. 1, the rear elevational view being a mirror image thereof.

FIG. 3 is a right side elevational view of the latch turn mechanism of FIG. 1, the left side elevational view being a mirror image thereof.

FIG. 4 is a top plan view of the latch turn mechanism of FIG. 1; and,

FIG. 5 is a bottom plan view of the latch turn mechanism of FIG. 1.
